VENETIAN BLIND

Rudolph Cusumano, Los Angeles, Calif.

Application November 20, 1944, Serial No. 564,231

4 Claims. (Cl. 160—34)

1

My invention relates to Venetian blinds of the type well known as including a plurality of spaced slats supported in spaced relation by ladder tapes, the slats being raised and lowered by cables or cords. In all such blinds, the slats are held in any raised or lowered position by fastening the raising or lowering cord or cable on a suitable anchoring device usually attached to a window or door jamb or other structural part of a building. The objections to this necessity of manipulation are many, and chiefly the time and trouble involved in loosening the raising and lowering cord or cable from its anchorage, operating the cord to effect the elevation or descent of the slats and the wear and tear on the operating medium.

The objects of the present invention are to provide a Venetian blind in which the slats thereof may be raised and lowered manually, without the use of cords or cables and in which the slats may be retained in any adjusted position, without locks or supplemental anchorage.

Another object of the invention is to provide in a Venetian blind, a means for counter-balancing the weight of the blind in any raised or lowered position.

Another object of the invention is to provide in a Venetian blind a spring mechanism, providing tension by which the blind is held counterbalanced in any position between the limits of its movement and an adjustment by which such tension in the spring may be varied according to the weight of the blind.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangement of parts, which will more fully appear in the course of the following description. However, the drawings merely show, and the following description merely describes embodiments of the invention which are given by way of illustration or example only.

In the drawings, like reference numerals designate similar parts in the several views.

Fig. 1 is an elevational view, partly in section of a device embodying my invention.

Fig. 2 is a top plan view.

Fig. 3 is an enlarged section on line 3—3 of Fig. 2.

2

Fig. 4 is a top plan view of a modified form of my invention.

Fig. 5 is a fragmentary elevational view showing the suspension means for the slats and

Fig. 6 is a section on line 6—6 of Fig. 5.

In a general sense, the invention comprises a Venetian blind of usual structure, suitably suspended, as from the upper jamb of a door or a window or other opening, or from a housing that may be attached to the frame work of a window or door. The slats are operable to raised or lowered position by rotatable or oscillatable means, to which cables or cords are connected, and the rotatable means is under tension and furnished with means by which the tension may be regulated and adjusted in accordance with the weight of the blind in any position of its movement, so that the blind, when manually raised or lowered, will remain in such position without further aid.

In a specific sense, the invention is shown as comprising a casing or enclosure 10, open at the top. The enclosure which may be a structural part of a building, is provided with bottom openings, around which are positioned guide members or eyes 11, secured to the floor 12 of the enclosure 10. Wire ropes or cables 13, secured to the bottom rail 14, Fig. 6, of the blind 15, pass through said guide members or eyes 11 and over pulleys 16, hung from the under side of cross bars 17, connecting the top of the sides of the enclosure. The ends of said wire ropes or cables 13, are secured to opposite sides of and in a cylindrical groove 18, that forms a part of a cone member 19, hereinafter more specially referred to. The wire ropes or cables 13, pass through openings in the slats 20, of the blind 15, which comprises said slats 20, ladder tapes 21, for supporting said slats 20 in spaced relation, and a bottom rail 14, to which the wire ropes or

cables 13 are attached in any convenient manner, whereby the rail 14 and consequently a portion of the slats 20 or all of them are held in raised or lowered position by the means detailed later herein. The tapes 21, supporting the slats 20, are secured at the top to cylindrical carriers or elements 23, that are mounted or fixed upon a common shaft 24, at spaced points thereon. The shaft 24 operates in bearings 25, and one end thereof is provided with a gear 26, in mesh with a worm 27, on a shaft 28, in and extending beyond the enclosure or housing 10. The extended end of said shaft 28, mounts a grooved pulley 29, or other means, over which extends preferably an endless line, or rope 30, which is operable by pulling on one or the other of the paral-

40
45
50
55

lel portions thereof to tilt the slats 20 in one direction or another. The aforesigned cone member 19, which is journaled in a member 19' and in a bearing plate 19'' is provided with a continuous spiral groove 31, more clearly shown in Fig. 3, in which is arranged to thread an end portion of a block line 32, which is under tension, as of a spring 33. In the form shown in Fig. 1, the other end of the block line 32, is anchored as suggested at 34 and the intermediate portion of the line or cable 32 passes over a pulley block connected to said spring 33 and pulley block 36 fixedly secured in said housing 10 in spaced relation to said block 35. In this manner, the tension of the spring is reflected in the cone member 19 through the block line or cable 32, the cone member being rotated during the manual elevation of the blind, thus causing the block line 32 to wind up to the greatest diameter of the spiral groove 31 and the wire ropes or cables 13, to wind on the cylindrical spool or groove 18. In this wise, that is, owing to the progressive winding of the block line on the tape or cone member 19, and toward the greatest circumference thereof, the tension on the line is equalized with the weight of the blind and the ratio of tension to the weight of the blind is maintained at all times, thus preventing any sudden acceleration of speed in the elevation of the blind as it approaches its top or uppermost position. In drawing down the blind, the block line 32 rotates the cone member 19 in the opposite direction, as it unwinds from the grooves 31, thereby placing the spring 33 under a progressively decreasing tension, which, however, is at all times proportioned equally to the weight of the blind. Thus the blind may be raised or lowered as desired, with small effort, and maintained in adjusted position without any supplemental means.

The tension of the spring 33, when the system is connected as explained, may be adjusted by any means, as a turnbuckle 37. It is believed clear, without further illustration that the simple pulleys or sheaves 35 and 36 may be multi-grooved or otherwise compounded to exert greater force or alter the rate of motion of the block line 32 and the cone body 19.

The form in Fig. 4, differs from the form heretofore described, in the employment of a torsional spring 40, contained and housed in the usual manner of a conventional spring type roller 41, but without the ratchet and pawl mechanism. The roller 41 is mounted to rotate in bearings 42. The shaft 24, which is journaled in suitable bearings 43, is provided with enlargements or drums 44 upon which are arranged to wind the wire ropes or cables connected with the bottom rail 14. Upon the shaft is fixedly mounted a cone member 45, provided with an exterior continuous spiral groove 46, in and from which is adapted to wind or unwind a cable or cord or other flexible means 47, that is paid out from or wound upon said roller 41, against or by the tension of the spring 40. The result attained by this form is practically identical with the result attained by the device shown in Figs. 1 and 2. In this latter form where the wires or cables carrying the bottom rail 14 are mounted to wind on and off the drums 44, it is possible to mount or attach these carrying wires to the outside ends of both the top and bottom rails, as illustrated in Fig. 5, and this arrangement leaves the slats 20 of the blind free to be removed from the ladders or tapes 21. Where the top and bottom rail of the blind are exposed, and the bottom rail is

used to lift the blind, as it must be in the present instance, it is desirable to coat, cover or encase the wood or metal rail in a soil-proof material or in one from which stains, dirt and marks 5 are easily removed. Such a cover, coat or case may be a plastic, as suggested at 48, in Fig. 6. Obviously, the lower rail 14 may be composed of plastic material. The upper rail 49, where exposed, as shown in Fig. 5, may constitute a tilt rail for tilting the slats forwardly or rearwardly 10 by any means.

It is believed clear without further illustration, that in this latter form of the invention, shown in Fig. 4, the bottom rail and the operating wires 15 or cables may be housed to slide in window or door jambs, and thus be invisible; also the tilting mechanism heretofore referred to, may likewise be housed and only the operating member extended in convenient access to or reach of the operator.

While I have illustrated and described what I now regard as the preferred embodiment of my invention, the construction is, of course, subject to modifications without departing from the spirit and scope of my invention. I, therefore, do not wish to restrict myself to the particular form of construction, illustrated and described, but desire to avail myself of all modifications that may fall within the scope of the appended claims.

Having thus described my invention, what I desire to secure by Letters Patent of the United States is:

1. In a Venetian blind including a plurality of slats; ladder tapes upon which said slats are supported and a bottom rail; the combination of a casing; a shaft journaled in said casing, spaced cylindrical members fixed on said shaft to support said tapes; a cone-shaped member rotatably mounted in said casing and having a cylindrical groove and a continuous spiral groove; flexible means connected with said rail to opposite sides of said cylindrical groove; a spring fastened at one end to said casing; and a cable connected to and tensioned by said spring, said cable connected to and operable in the spiral groove of said member to regulate the tension of said spring in accordance with the weight of the blind and means to oscillate said shaft to cause the cylindrical members thereon to vary the angle of said slats.

2. In a Venetian blind including a plurality of slats; ladder tapes upon which said slats are supported and a bottom rail; the combination of a casing, a shaft journaled in said casing and provided with cylindrical members to support said tapes, a gear on said shaft, means engaging said gear and manually operable to oscillate said shaft and tilt said slats, a spirally grooved cone-shaped body journaled centrally in said casing having a cylindrical portion provided with a groove, flexible means connecting said rail and cylindrical groove, means to cause said body to oscillate as the blind is raised and lowered to wind said flexible means on and off the spiral groove, including a spring fixed at one end to and in said casing, a block at the other end of said spring, a sheave block fixed in said casing, a line tensioned by said spring and threaded over said blocks, said line having one end fixed to and in said casing and the other end anchored to said body in said spiral groove, thereby to cause said line to wind from and into said spiral groove as the blind is raised or lowered and to regulate the line pull on said spring in accordance with the weight of

the blind, and means to adjust the tension of said spring.

3. In a Venetian blind including a plurality of slats, ladder tapes upon which said slats are supported and a bottom rail; the combination of a casing, a horizontal shaft journaled in said casing and provided with cylindrical means to support said tapes, a gear on one end of said shaft, a transversely disposed shaft journaled in and extending beyond said casing and provided with a worm in engagement with said gear, a pulley on the end of said transverse shaft, flexible means carried by said transverse shaft-pulley to tilt said slats, a single spirally grooved conoidal body journaled in said casing and provided with a cylindrical groove, flexible means connecting said rail to said cylindrical groove, a spring fixed at one end to and in said casing, a block at the other end of said spring, a block fixed in said casing, a line tensioned by said spring and threaded over said blocks, said line having one end fixed to and in said casing and the other end anchored to and in said spiral groove, thereby to regulate the line pull of said spring as the blind is raised and lowered, and an adjustment means in said casing for regulating the tension of said spring.

4. In a Venetian blind including a plurality of slats; ladder tapes upon which said slats are supported and a bottom rail; the combination of a casing, a shaft journaled in said casing, spaced cylindrical members fixed on said shaft to support said tapes, a single conoidal body journaled in said casing having a cylindrical portion pro-

vided with a groove and a continuous spiral groove, pulleys in said casing in line with said tapes and with the cylindrical groove of said body, flexible means threading over said pulleys and connecting said rail to opposite sides of said groove on the cylindrical portion, means to cause said conoidal body to oscillate and to alternately wind said flexible means on and off said cylindrical groove as the blind is raised and lowered, comprising a line attached to said body in said spiral groove, a horizontal spring, anchored at one end to and in said casing and at the other end connected to said line to maintain said line in tension, said spiral groove automatically adjusting the tension of said spring to the weight of the blind, means to regulate the tension of said spring, and independent manual means for operating said shaft to adjust the angle of said slats independently of said flexible means.
